RUSSELL A. FRISBIE, OF MIDDLETON, CONNECTICUT, ASSIGNOR TO THE J. & E. STEVENS COMPANY, OF CROMWELL, CONNECTICUT, A CORPORATION

TOY PISTOL

Application filed August 7, 1929. Serial No. 384,021.

My invention relates to improvements in toy pistols, of the form that is adapted to fire paper caps in strip form and supplied in coil form, and the object of my improvement is to produce a toy pistol of relatively few parts, that is easy to produce and particularly easy to assemble, and that is efficient and reliable under conditions of use.

In the accompanying drawing:—

Figure 1 is a group view showing all of the parts that go to make up the complete pistol embodying my invention, showing the outside views of the two cast iron casing parts; two other cast parts, respectively the trigger and the hammer; separable spring parts comprising as coil springs the trigger spring and the main or hammer or firing spring; and the sheet metal tape guide spring.

Fig. 2 is a second group view showing the insides of the two casing parts.

Fig. 3 is a sectional view on the line 3—3 of Fig. 4 showing the casing spring that is fixedly secured to the right casing part by a rivet and serves to hold the two casing parts together, the cooperating portions of the casing parts being also shown.

Fig. 4 is an inside view of the right main casing part with all of the operating elements assembled therein; the cap tape also being shown; the trigger spring being indicated substantially complete, broken lines showing the location of concealed portions thereof; and the trigger member being broken away adjacent the fixed end of said trigger spring, thus disclosing the engagement of said fixed end with the opposed cooperating lug on the casing part.

Fig. 5 is a view generally like Fig. 4, with the parts in a different position.

Fig. 6 is a side view of a modification of the hammer, the correspondingly modified portion of the trigger member that cooperates therewith being indicated by means of broken lines.

Fig. 7 is a fragmentary inside view of the modification of the main casing and the correspondingly modified tape guide spring, showing the supporting arm of the guide spring and the cooperating posts and lugs on the casing part.

Fig. 8 is a sectional view on the line 8—8 of Fig. 7, showing generally the detail of the engagement of the supporting arm of the modified tape guide spring with the middle post on the casing part.

My improved toy pistol is adapted for firing as a repeater paper caps that are provided in the form of a coil 10, said coil being mounted on a post 11 that is provided in the interior of the handle portion 12 of the pistol structure. The tape end portion 13 is led upwardly along a curved contact face portion or guide face portion 14 of the free end branch 15 of the tape guide spring 16; thence between the fixed tape stop or grip face 17 and the extreme or tip end 18 of said free end branch 18; and finally between the anvil 19 at the top and rear and the opposed end face 20 of the hammer 21, the latter being in the form of an elongated cast block that is extended generally along the barrel portion 22.

The trigger 23 is provided with an opening 24 by which it is operatively mounted on a post 25; has a set of generally radially directed arms, three in number; and one of said arms serves as the tape feed arm 26, being generally rearwardly directed and cooperating with the curved guide face 14 already mentioned. The others of said arms comprise the downwardly directed arm 27 that serves as the trigger and the upwardly directed arm 28 that operates the hammer 21, the tip end 29 of the body portion thereof engaging with a notch 30 therein.

The trigger spring 32 is made of wire; has a body of coil form; has the fixed end 34 engaged with a stop 35 that is in the form of a lug that is integral with the casing part 36, which, as shown, is the right casing part. Said lug 35 overhangs an opening 37 in the casing part 36 and is in slightly spaced relation to the adjacent face 38 of the casing wall, whereby a structure is provided that permits of tucking the wire spring end 33 under the lug, involving bridging by the wire end the corresponding portion of said opening 37.

The moving end 39 of the trigger spring 32 is incorporated in the structure of the trigger arm 27.

The to and fro movement of the trigger 23 is limited by the tape feed arm 26; the tip end 40 thereof engages with the tape in effecting the feeding; the feeding movement thereof is upward; such upward movement being limited by the bottom edge 41 of the structure of the fixed tape stop 17; and the movement in the downward direction being limited by making contact with a fixed post 42 on the casing part 36.

The movement of the trigger 23 is effected in one direction by pulling on the trigger 27 and the return movement is effected by the trigger spring 32, and these parts are operatively supported by the right casing part 36, the post 25 being integral therewith. As viewed from the inside with the left casing part 43 removed the movement of the trigger for firing is counter-clockwise. Also, the trigger spring 32 is located back of the trigger, being housed between the said trigger 27 and the casing wall.

In front of the trigger 27, also in contact with the post 25, is the fixed arm or end portion of the main spring 44 to be described.

The engagement of the trigger with the post 25 by means of the opening 24 is such as to provide a floating support; said opening being relatively large, particularly in the longitudinal direction; the trigger structure being pulled away from the post initially for each of the two rotative movements; such movement being continued until the post makes contact with the opposite end wall of the opening; following which the real rotative movement begins. Thus the rear end wall 45 and the front end wall 46 of the opening 24 come into play alternatively as pivotal bearing faces.

40 The open space above the end walls or corners 45 and 46 terminates at a third corner 47 and permits of limited vertical movement bodily of the trigger 23 so that it can drop below the hammer 21, as is desirable, during part of the return movement after release of the trigger arm 27.

Such return movement is effected by the trigger spring and is in the clock-wise direction, and during this movement the tip end 29 of the body portion arm 28 rides along the under face 49 of the hammer 21 until it comes into registration with the notch 30 in the hammer. During the firing movement the firing arm 28 moves counter-clockwise in engagement with the notch 30 until the hammer is released in substantially the usual manner by disengagement of the tip 29 from the notch 30.

60 The hammer is guided for straight to and fro longitudinal movement and the firing is effected by the main spring 44 through the medium of the free end portion 51 of the main spring 44 that is operatively housed in a suitable recess 52. Said main spring 44 is made of 65 wire, has a body of coil form that is mounted

on a post 53 that is located adjacent the opening 54 for the trigger arm 27, and the fixed end portion 55 thereof extends from the supporting post 55a generally rearwardly and across the face of the trigger 23. Said wire end portion 55 is tucked under an overhanging post or lug 56 and makes bearing contact with the pivotal post 25 for the trigger, on the upper side thereof.

To assist in guiding, the trigger 23 is provided at the tip 48 with a diminutive flange or wing 57 that overhangs the adjacent portion 58 of the side face of the hammer 21 and slides therealong during the to and fro movement.

Referring to the tape guide spring or backing spring 16, this is generally U-shaped, the guide portion being provided by the free end branch 15. The supporting branch 59 projects upwardly from the bottom junction portion 60 and engages with a set of three posts, respectively, first, the post 62 at the right, next above the post 63 at the left, and then, at the top end portion 64, the post 65 at the right.

The top end portion 64 and the cooperating post 65 are shaped, as shown, to provide a knife-edge engagement that operates as a pivotal connection and also as positioning means.

The middle or intermediate post 63 and the opposed portion 66 of the spring 16 have, besides the side by side engagement, may be designated as an under-cut engagement to hold the spring against outward movement.

As shown, the spring 16 is provided with an integral lip 67 that is adapted to engage with a notch or the like. Actually, the post 63 is cast so that a portion 70 thereof overhangs part of an opening 68 in the adjacent supporting wall portion 69 of the casing wall 105 and which overhanging post portion 70 is likewise outwardly spaced or stepped from said wall portion 69. Thus there is provided means for permitting the holding lip or wing 67 to be slipped under the overhanging portion 70 and at the same time bridging a part of the opening 68 for effecting the holding of the tape guide spring 16.

All of the moving parts described are operatively mounted on the right casing part 36. The left casing part 43 serves merely as a cover therefor, except that the interior thereof may be provided with ribs and ridges and the like for assisting in guiding some of the moving parts, as is generally common, and also with edge structures for mating with the edges of the other part.

Spring means are provided for holding the casing parts together in the form of a spring 71 of flat material that is held on a platform 72 on the right casing part 36 by means of a rivet 73, and which engages with the walls of an opening 74 in the left casing part 43. Said spring 71 is U-shaped, with up-standing arms 75 that have reverse curves so as to provide 120

opposed recesses 76 that are just below or back of outwardly flaring tip ends 77. The walls 78 of the opening 74 are shaped generally to correspond, though they are more nearly V-shaped, one on each side, with the apices opposed, so as to permit of virtually snapping the parts together and pulling them apart in opposition to the resiliency of the spring 71.

10 The means described for cooperation of the backing spring 16 and the intermediate post 63 to prevent outward movement from the casing, involving a lip or wing 67 on the spring and the overhanging portion 70 of said post 63 adjacent the junction of said post with the casing wall portion 69 is satisfactory as to operation, but involves a projection along one of the edges of the spring which can be dispensed with by use of the 15 modified construction shown in Fig. 8. In this construction the supporting post that corresponds to post 63 is shaped to provide an under-cut portion 80 that is defined by an inclined face 81 that effects the holding of the tape guide spring 82. Said tape guide spring 82 has its lower or inner part 83 swaged so as to be deflected laterally for effecting holding engagement with said face 81. Thus the inner or bottom edge portion 84 20 of the spring 82 is off-set relatively to the general direction or plane of the spring 82. Thus means are provided for holding the tape guide spring in place without adding to the width of the strip spring material of 25 which the spring is formed.

Another modification is provided in the detail of the overlying of the trigger member 23 relatively to the structure of the hammer 21, which is described as being in the form 30 of a wing or flange 57 that is opposed to the adjacent side face portion 58 of said hammer. In lieu thereof the flange or wing 57 is omitted and is virtually replaced by a web 35 85 on the hammer 86 along which the firing arm 87 of the trigger member 88 rides and which web 85 extends along the structure of the hammer 86 back of the firing notch 89 and the adjacent open free movement space 90 alongside the contact edge or face 91. 40 That is to say, instead of having the firing notch 89 extend across the under edge portion 92 of the hammer the said notch is in the form of recess in the side face of the hammer, the said web serving as the back wall 45 or bottom of the recess. When released from the firing notch 89 the tip 93 of the trigger member 88 rides along the contact face 91 and the back or bottom of the adjacent space 50 is filled by an extension of the web so as to define a recess in the hammer for the arm 87.

The construction just described provides a stronger structure for the hammer. In both forms a part of the trigger member over 55 hangs a part of the hammer so as to tend to

hold the hammer in the right or main casing part, particularly the rear or firing end portion of said hammer.

Other means operate more particularly on the front end portion of the hammer to hold the same in the casing part, in the form of the free end portion or free arm 51 of the main spring 44 already mentioned and which is operatively housed in the recess 52 in the side face of the said hammer 21. Said free 60 arm 51 rides on the opposed material of the hammer that constitutes the bottom or back wall of the spring engaging recess 52. A further consideration of the details shows that, having reference to the main spring 44, this spring also operates to hold the trigger member 23 in place by its fixed arm 55 that overlies and extends across the face of the trigger member 23 as already mentioned. Said fixed arm 55 is positively held in place 65 by its engagement with the overhanging post or lug 56 and the post 25 that serves as the pivotal post for the trigger member.

An important detail as to the construction and operation of the trigger member 23 is 70 the incorporation in one of the arms thereof of the free or moving end 39 of the trigger spring 32.

Another important detail of construction and operation, involving the floating movement of the trigger member is that immediately after release of the finger from engagement with the trigger proper the trigger spring starts the floating movement such as to carry the part away from the tape backing spring 75 and the cap tape opposed thereto, thus avoiding any drag on the tape.

I claim as my invention:—

1. In a toy tape pistol, a casing part having a tape holding lug, a tape guide spring having a free tip end opposed to said lug for pinching the tape, a trigger member supported from said casing part for rotative movement and provided with a tape engaging arm that is located generally below said lug, said spring having a portion adjacent said arm and opposed thereto, and the parts being constructed and arranged so that said arm will swing along said portion for feeding tape therealong and upward, will push said free end tip away from said lug, and will push the tape into the space between said tip and lug, and, responsive to return movement, will release said spring for effecting the pinching of the tape.

2. In a toy tape pistol as described in claim 1, a trigger spring serving to effect such return movement.

3. In a toy tape pistol as described in claim 1, an anvil and a hammer held thereagainst by a main spring and provided with a trigger notch, said trigger member having a hammer arm for cooperating with said notch, said hammer having a contact face for the tip of said hammer arm adjacent said notch, a stop

- and guide lug for engaging with said tape engaging arm for limiting such return movement and for permitting sliding movement of said trigger member, and the support for said trigger member comprising a post on the casing and an enlarged opening in the trigger member for permitting limited floating movement of the trigger member.
- 5 4. In a toy tape pistol as described in claim 1, a stop lug for limiting such return movement, and a spring tending to hold said trigger member against said stop lug.
- 10 5. In a toy tape pistol, a casing part, a tape guide spring supported from said part by an arm structure that is engaged with a set of posts, one of said posts having a part that is separated from the casing wall by a recess-like space, and said spring having a holding wing or the like that is tucked into 15 said space.
- 20 6. In a toy pistol, a main pistol casing part and a cover pistol part, a holding spring secured to said main part and having arms up-standing that are shaped to provide opposed 25 generally V-shaped parts, and said cover part being provided with an opening that has opposed border walls that are individually V-shaped and adapted to cooperate with said arms for holding the parts together.
- 25 7. In a toy tape pistol, a U-shaped flat strip sheet spring structure having one arm that serves as a support and another arm in the form of a free arm that under conditions of use is opposed to the tape strip and to tape 30 engaging and feeding means, means for supporting said free arm for to and fro movement under such conditions of use comprising a set of posts for cooperating with said one arm, said one arm being bent and shaped 35 40 to facilitate such cooperation, a casing side wall portion serving as the support for said posts, one of said posts being constructed and arranged so that its outer tip end portion overhangs the inner supporting end portion at or adjacent the junction with said casing side wall portion so as to provide an under-cut face portion adjacent said junction, and the portion of said flat strip that is 45 50 opposed to said one post being swaged in the direction of the cross-section for effecting a holding engagement with said under-cut face portion.
